UNITED STATES PATENT OFFICE.

AXEL R. GUSTAFSON, OF CHICAGO, ILLINOIS.

IRONING-MACHINE.

1,086,292.

Specification of Letters Patent.

Patented Feb. 3, 1914.

Application filed April 22, 1913. Serial No. 762,772.

To all whom it may concern:

Be it known that I, AXEL R. GUSTAFSON, a citizen of the United States, residing at Chicago, in the county of Cook and State of Illinois, have invented certain new and useful Improvements in Ironing-Machines, of which the following is a specification.

My present invention relates to improvements in ironing machines, and is designed especially with the purpose of providing these machines with easily manipulated and smoothly operated parts.

The invention relates especially to the movement and supporting parts of the carriage upon which the compression rollers are supported, to a special attachment for use in ironing lace curtains or similar articles, and to other novel combinations of parts as will appear hereinafter.

In the accompanying drawings I have illustrated one complete example of the physical embodiment of my invention constructed according to the best mode I have so far devised for the practical application of the principles of the invention, and one which has proven highly satisfactory in actual use.

Figure 1 is an end view of an ironing machine embodying the present invention. Fig. 2 is a front elevation of the machine, broken away for purposes of illustration. Fig. 3 is a side elevation of the machine looking in a direction opposite that of Fig. 1. Fig. 4 is a detail, enlarged view of a roll for attaching lace curtains when ironing. Fig. 5 is a side view of Fig. 4. Fig. 6 is an enlarged, detached view of a part of carriage for the compression rollers, and the actuating lever. Fig. 7 is a transverse sectional view of a portion of the carriage and track of Fig. 6.

In the embodiment of my invention as illustrated, the machine is supported upon the side frames 1, 1 which are of usual metallic construction, and the heater roller 2 is journaled between these frames as usual. The heater roller is supplied heat from the burner pipe 4 as usual, and is driven from the motor 5 through the medium of the pulley 6, belt 7, pulley wheel 8 on the shaft 9 and the pinion 10 thereon which engages the larger gear 11 on the trunnion 11' of the heater roller. The trunnion 12 of the heater roller is supported in the side bracket 13 attached to the upper side plate 15 of the machine frame.

A clothes receptacle 16 is supported, below the feed table 17, in convenient position for use by the operator when working the ironing machine.

The two compression rolls 18 and 19 are supported by their journals 20 and 21 in the carriage 22, and are furnished with the usual padding or canvas covering. The carriage is arranged to move obliquely to the axis of the heater roller, and at each end is provided with a pair of wheels 23, 23, which roll upon the side flanges 24 of the plates 15. The carriage with its compression rollers thus travels upon an inclined track toward and away from the heater roller. The carriage may be moved away from the heater roller by means of the lever mechanism comprising the two side arms 25, 25 which are connected by the cross bars 26, 75 and pivoted at 27, 27, in the side plates 15. Each lever arm 25 is provided with an anti-friction roller 28 which engages the cam face 29 on the carriage 22, and when the lever arms 25 are pulled over as in dotted line position Fig. 1, the moving contact of the roller 28 on the cam face 29 lifts the carriage upon its track, and is held in recess 29'. A pair of threaded rods 30 are screwed through ears 31 on the side plates 15, and each rod extends through a perforation in the carriage to guide a coiled spring 32' which is located between the ear 31 and the carriage to force the compression rollers against the heated roller. The compression rollers are revolved from the large wheel 11 by means of the smaller gears 33, 34.

The articles are fed to the rollers from the feed table 17, as usual and pass between the rollers which are revolved from the motor 5.

For ironing lace curtains and similar articles I provide a roller 35, with pins 36 projecting therefrom, and journaled by its pintles 37 in the slotted plates 38. These plates are attached to the feed table, at its opposite end corners by means of turn screws 39.

When operating the ironing machine, the attendant, having lighted the burner to heat the heater roller as required, starts the motor which revolves the rollers through the train of gears as described. The carriage is in position to locate the compression rolls in their proper relation to the heater roll, 110 and the carriage and compression rollers held in this relation by gravity and the

springs. The clothes are fed to the machine by the operator as usual, and drop into the proper receptacle.

When feeding lace curtains, the curtain is first attached to the roll by means of the line of pins, and the roll suspended by its pintles in the slotted side plates 38. The curtain is then rolled upon this roller. The filled roller is removed, reversed and then replaced in the slotted plates, so that the free end of the curtain may be fed to the ironing rollers. When first entered between the ironing rollers the curtain is guided and handled by the operator, but after passing between them for a considerable distance, the curtain is drawn from its roll by the movement of the ironing rollers, and in this manner is fed with facility and simplicity to and through the rollers.

The compression rollers are held in place with resiliency and respond easily to the passage of the articles between the rollers.

The ironing operation may be suspended by throwing the levers and lifting the carriage and its compression rollers away from the heater roll, as will be understood.

Having thus fully described my invention what I claim as new and desire to secure by Letters Patent is:—

The combination with a frame having an inclined track and a heated roller, a carriage having wheels on the track, compression rollers on the carriage, guide rods between the frame and carriage and springs on said rods, a cam edge on the carriage, and a lever engaging said edge whereby the carriage may be moved to render the compression rollers inoperative.

In testimony whereof I affix my signature in presence of two witnesses.

AXEL R. GUSTAFSON.
